SALIVA EJECTOR

Henry F. Boeger and Walter J. Van Rossem, Los Angeles, Calif., assignors to Surgident, Ltd., Los Angeles, Calif., a corporation of California

Application April 28, 1933, Serial No. 668,400

6 Claims. (Cl. 32—33)

This invention relates to saliva ejectors such as used by dentists for carrying off saliva from a patient's mouth while the dentist is working on the patient's teeth. For this purpose, it has been 5 the practice to employ a suction tube having a goose neck which is hung over the patient's lower jaw, and suction developed in the tube, draws saliva in through inlet openings at the lower end of the goose neck. The action of this type of 10 ejector is not entirely satisfactory, because the suction at the inlets tends to draw in the adjacent flesh, and thereby close the suction inlet and cause the tube to attach itself by the suction to the flesh within the mouth.

15 The general object of this invention is to improve the general construction of saliva ejectors of this type; also to provide improved means carried by the ejector tube for providing a rest to support the patient's upper jaw in an open position; also to provide a clamp to be adjustably 20 secured on the shank of the ejector tube for carrying the rest that supports the upper jaw.

A further object of the invention is to provide 25 an improved construction for the clamp, and also to provide it with an extension or extensions to rest upon the patient's chin to keep the shank of the tube in a substantially vertical position, and prevent the tube from swinging over against the patient's chin.

30 A further object of the invention is to provide means at the suction end of the tube, for supporting an absorbent material in a position to enable the absorbed saliva to be readily carried off by the tube.

35 Heretofore, a clamping device with a spring has been employed on a tube of this kind for supporting the upper jaw rest, but it has been found in practice, that there is a tendency for the upper jaw to release the spring clamp. One of the objects of this invention is to provide a construction for the rest, which will overcome this difficulty.

Further objects of the invention will appear hereinafter.

45 The invention consists in the novel parts and combination of parts to be described hereinafter, all of which contribute to produce an efficient saliva ejector.

A preferred embodiment of the invention is 50 described in the following specification, while the broad scope of the invention is pointed out in the appended claims.

Referring to the drawing:

Figure 1 is a side elevation in partial section of 55 a saliva ejector embodying our invention, and indicating its relation to the jaws of the patient when in the patient's mouth. In this view, the suction head of the tube is shown in cross-section, illustrating the way in which the absorbent material is held by it.

Figure 2 is a side elevation illustrating another embodiment for the suction head.

Figure 3 is a cross-section upon an enlarged scale taken about on the line III—III of Figure 2, and further illustrating its details.

Figure 4 is a vertical section through a suction head for the tube of a modified form.

Figure 5 is a section taken on the line V—V of Figure 4, further illustrating details.

Figure 6 is a horizontal section taken on the line VI—VI of Figure 1, and further illustrating the construction of the adjustable clamp mounted on the shank of the tube.

Figure 7 is an elevation of the body of the clamp as viewed from the right side of Figure 6, 15 but representing the same with the two plates that carry the clamping jaws, removed from the clamping plate.

Figure 8 is a side elevation of one of the wing plates represented as removed from the clamping 20 plate.

Figure 9 is a side elevation illustrating a suction tube of the flexible type referred to above, and illustrating an improvement which we apply to such a tube in order to enable it to cooperate 25 effectively with a clamp such as illustrated in Figure 6.

Figure 10 is a side elevation and partial section illustrating another embodiment of the invention.

Figure 11 is a plan illustrating another embodiment of the invention.

Figure 12 is a vertical section taken on the line 12—12 of Figure 11.

Figure 13 is a bottom plan of an inner sleeve 35 illustrated in Figure 11.

Figure 14 is a horizontal section on the line 14—14 of Figure 12, but with the inner sleeve removed.

Referring more particularly to the parts, and 40 especially to Figure 1, 1 indicates a suction tube having a shank 2 below, and having its upper end bent to form a goose neck 3, the lower end of which is formed into a suction head 4. In accordance with our invention, we provide the lower 45 end of this suction head with an inlet opening 5, which, in the embodiment of the invention illustrated in Figure 1, is formed by the mouth or lower end of the bore of the tube. In accordance with our invention as applied to a tube of this 50 type, we provide means for holding a piece 6 of absorbent material, so that it extends in a direction transverse to the goose neck, but adjacent to the suction inlet 5, so that saliva that is absorbed by the absorbent, will be carried off by the tube. 55 In the present instance, we provide the goose neck near its lower end, with a sleeve 7, the lower end of which extends laterally to form a rudimentary cup 8 having an upwardly turned edge 9, and having an inlet opening 10 in its 60

bottom. Opposite this inlet opening, the sleeve 7 is provided with a movable collar 11 that carries a lateral extension or finger 12 that projects out over the cup, and which may cooperate with the cup to clamp the piece 6 of absorbent material which may be in the form of a roll. This roll can be bent around to fit into the lower jaw adjacent the teeth.

In clamping the roll in place, the collar 11 can be shoved upwardly on the sleeve 7, and the collar and sleeve may be provided with means for yieldingly holding the collar in place on the sleeve after it has been shoved down against the absorbent roll. For this purpose, the collar 11 may be made friction-tight on the sleeve. If desired, the sleeve 7 may be swiveled on the lower end of the goose neck. This may be accomplished by providing an annular groove 13 on the outer side of the neck, and providing the sleeve 7 with a small projection 14 to engage in this groove. The projection 14 however, is very small, so as not to interfere with forcing the sleeve over the lower end of the tube.

As illustrated in Figure 1, the suction head for holding the absorbent material, is represented with the cup 8 projecting away from the shank 2 of the tube. However, if desired, the cup may project in the other direction.

On the shank 2 of the tube, we provide a clamp 15 which is mounted on the tube for vertical adjustment. This clamp is preferably provided with a guard 16 to engage the patient's chin to hold the tube 2 in a substantially upright position, and to prevent the tube from swinging sidewise. This guard comprises two oppositely disposed outward extensions preferably in the form of bent plates 17 that have cheeks or "pads" 18 to lie against the patient's chin. The clamp 15 includes a body or clamping plate 19 (see Fig. 7), which is preferably of elongated rectangular form, and attached to this plate we provide wing plates 20 which are spring-pressed and which are provided with jaws 21 respectively, to clamp the shank 2 of the tube. These jaws may be mounted in any suitable manner to accomplish their purpose. In the present instance, the clamping plate 19 is bent so as to form a rudimentary saddle 22 that rides on one side of the shank 2, while the jaws 21 are disposed opposite to this saddle, and by the action of a coil spring 23 are urged inwardly to clamp the shank against the saddle.

In order to accomplish this, the wing plates are hingedly mounted on the clamping plate 19. While the hinge connections for the clamping jaws may be made in any suitable manner, we prefer to form them on two forks 24, which form a rest 25 for the patient's upper jaw. For this purpose the plate 19 is provided with means including four sockets 26 in which the forks 24 of the rest are secured. The sockets 26 on the same side of the plate 19 are separated from each other so as to expose portions of the forks 24, and at this point hinge sleeves 27 formed on the wing plates 20 are attached. These wing plates may have substantially the form illustrated in Figure 8, each wing plate being provided with two of the jaws 21 already referred to.

The rest 25 is preferably made of stiff wire bent at its upper end to form a head 28 capable of engaging the teeth of the upper jaw. For this purpose the head 28 is preferably bent to form a rudimentary socket 28a which receives the teeth in the manner indicated in Figure 1.

The rest 25 at its upper end is preferably off-

set inwardly as indicated in Figure 1. This offset brings the line of pressure of the upper jaw on the rest, into a plane which does not tend to disconnect the clamp from the shank 2.

This rest 25 is preferably secured in the clamp 5 on the side opposite to the guard 16.

In Figures 2 and 3, we illustrate another embodiment of the invention as regards the suction head. In this instance, the suction head involves the use of a reduced neck 29 formed on the lower end of the goose neck 30, said neck affording means for securing a suction inlet 31 in the form of a manifold having a plurality of orifices 32. This suction inlet 31 has a tubular sleeve 33 extending up from it, that is secured 15 over the neck 29, and this sleeve is provided with a slot 34 to align with an orifice or inlet opening 35 formed through the wall of the neck (see Fig. 3). Above the sleeve 33 a collar 36 is mounted, which is provided with an extension 37 20 in the form of a fan-shaped plate, and this plate may be provided with an opening 38 for facilitating passage of saliva through it and into contact with a roll 39 of absorbent material held under the plate 37.

25

In Figures 4 and 5, another embodiment for the suction head is illustrated, in which the lower end of the shank 40 of the suction tube is provided with a manifold inlet 41 having a plurality of suction inlets 42 aligning with corresponding orifices 43 in the wall of the shank 40. Above this suction inlet 41 a collar 44 is provided, which has a lateral extension 45 in the form of a rudimentary hook to engage the upper side of a roll of absorbent material. The inlet head 41 is 35 preferably of enlarged diameter at one point, to form a hip or knuckle 46 to engage the under side of the roll of absorbent material and to cooperate with the holder 45 to keep the roll in place.

40

In practice, sometimes the suction tube of the ejector is of flexible material in which case the shank does not cooperate very well with a clamp such as illustrated in Figure 6, because the material of the tube is soft. In Figure 9 we 45 illustrate means for overcoming this difficulty. In this view, 47 illustrates the body of the flexible tube having a goose neck 48, which can be bent around as desired to fit into the patient's mouth. In order to adapt such a tube to cooperate with a clamp such as illustrated, we provide it with an enveloping shank 50, which is preferably in the form of a sleeve of rigid material, such as brass. A relatively thin brass tube 55 may be used for this purpose. This sleeve 50 may be brazed or otherwise secured to the tube. It is not for the purpose of reinforcing the tube, but to insure that there will always be a straight shank on which the clamp can run freely. It should be understood that when these saliva 60 ejectors are in use, a hose is attached to the shank of the tube for conducting the saliva to a drain. It will be evident in using this saliva ejector, that the clamp 15 can be readily adjusted and secured in any position to hold the upper jaw of the patient easily in an open position, after the tube has been provided with a roll of cotton or other absorbent material. It will also be evident that the suction head can be swung 65 over in the patient's mouth either to the left side or the right side, to place it out of the way of the dentist's fingers when working in the patient's mouth.

60

It is desirable to have the goose neck of saliva 70 ejectors as small as possible, so as not to inter- 75

fer with the dentist working in the mouth. In Figure 10, we illustrated an embodiment of the invention in which the tube 51 is formed with a relatively small goose neck 52, at which the tube 5 is bent to a comparatively small radius. Beyond this goose neck the tube has a substantially horizontal shank 53 on the end of which a suction head 54 is mounted. The mounting for this suction head preferably includes an upper fitting 10 55 having a threaded nipple 56 that screws into the end of the tube, and this fitting 55 is provided with a bore 57 open on its under side to receive the upper end of a sleeve 58 which is thrust up into it from below. This sleeve has a 15 perforation 59 in its side to communicate with the tubular nipple 56. The sleeve 58 may be friction-tight in the bore 57, or it may be retained by providing it with a depression 60 to be engaged by a corresponding small projection 20 formed at the lower end of the bore.

The lower end of this sleeve 58 may be provided with holding means for the absorbent material such as that illustrated, and which may be substantially the same as that illustrated in 25 Figure 4. The lower end of the sleeve is provided with an inlet opening 61 on the side toward the absorbent material. The absorbent material, of course, is held under the extension 62. The extension 62 and the enlarged lower head or button 63 may be formed in one piece and rigidly secured to the sleeve.

In Figures 11 to 14, we illustrate another embodiment of the invention, in which the saliva tube has a goose neck 64, the shank 65 of which extends 35 downwardly so as to support an outer sleeve 66 within the mouth. This outer sleeve preferably has a convex face 67 on the side that is disposed inwardly in the mouth. In Figure 11, the dotted lines 68 indicate the contour of the patient's jaw. 40 This sleeve 66 is preferably cut away as at 69 on its outer side. This sleeve is supported by a swivel connection such as illustrated in Figure 10, on the shank 65, and the longitudinal axis of this sleeve is disposed in a substantially horizontal position. 45 This sleeve is capable of supporting an elongated absorbent material such as the roll 70 of cotton. The roll is pulled through the sleeve before the shank of the device is inserted in the patient's mouth. In order to facilitate the passage of saliva 50 up into the shank 65, the wall of the sleeve 66 is provided with a circumferential groove 71, and on its lower side a longitudinal groove 72 is formed and extends out to the ends of the sleeve. These grooves facilitate the passage of saliva up into a 55 tubular nipple 73 at the upper side of the sleeve, which is connected to the shank. If desired, an inner sleeve 74 may be provided, which is of light spring material. This sleeve is a split sleeve, and for this purpose is provided on its bottom side with 60 a longitudinal slot 75, which may be enlarged into an opening 76 at its middle point. This opening 76 facilitates the passage of saliva up through the tubular nipple 73. It will be noted that when the absorbent material is placed in position it virtually completes the duct leading into the head that conducts the saliva into the head. In other words, the inlet duct into the head will 65 not operate efficiently without the presence of absorbent material.

70 The inner sleeve 74 is held in the outer sleeve by means of a slightly enlarged counterbore 77, which forms two annular shoulders 78, which en-

gage the ends of the inner sleeve when it is in place.

It is understood that the embodiment of the invention described herein, is only one of the many embodiments this invention may take, and we do not wish to be limited in the practice of the invention, nor in the claims, to the particular embodiment set forth.

What we claim is:—

1. In a dentist's saliva ejector, the combination of a tube having a goose-neck to be hung in the patient's mouth, a clamp having spring-pressed jaws for clamping the tube, said clamp having means extending away from the jaws, said means having outer extensions in a plane removed 15 from the axis of the goose-neck for engaging the patient's chin, and a rest carried by the clamp extending upwardly and having a rudimentary socket at its upper end for engaging the teeth of the patient's upper jaw. 20

2. In a dentist's saliva ejector, the combination of a tube having a goose-neck to be hung in the patient's mouth, a clamp having spring-pressed jaws for clamping the tube, said clamp having a pair of members extending laterally therefrom 25 for engaging the patient's chin, operating to hold the goose-neck away from the patient's chin and a rest carried by the clamp extending upwardly and having a rudimentary socket at its upper end for engaging the teeth of the patient's upper jaw. 30

3. In a dentist's saliva ejector, the combination of a tube having a goose-neck to be hung in the patient's mouth, a clamp having spring-pressed jaws for clamping the tube, said clamp having a pair of oppositely disposed chin plates extending 35 therefrom for engaging the patient's chin at two separate points, and a rest carried by the clamp extending upwardly and having a rudimentary socket at its upper end for engaging the teeth of the patient's upper jaw. 40

4. In a dentist's saliva ejector, the combination of a tube having a goose-neck to be hung in the patient's mouth, a clamping plate having socket means formed thereon, a rest for the patient's upper jaw having a stem received in the socket 45 means, and a pair of wing plates hingedly mounted on the clamping plate, with jaws for clamping the side of the tube, and a spring associated with the wing plates for pressing the same in a direction to clamp the tube. 50

5. In a dentist's saliva ejector, the combination of a tube having a goose-neck to be hung in the patient's mouth, a clamping plate, a rest for the upper jaw of the patient having a stem with a pair of forks secured to the clamping plate, and 55 a pair of wing plates hingedly mounted on the forks adjacent the clamping plate, said wing plates having jaws for clamping the side of the tube, and a spring associated with the wing plates for pressing the same in the direction to clamp 60 the tube.

6. In a dentist's saliva ejector, a tube having a goose-neck extending downwardly from its upper end, said goose-neck having a substantially horizontal extension, a fitting secured to said extension, and a suction head carried by the fitting, said suction head having means for engaging the upper and lower sides of an absorbent material for holding the same. 65
